US00D846433S

(12) **United States Design Patent** (10) **Patent No.:** **US D846,433 S**
(45) **Date of Patent:** **** Apr. 23, 2019**

(54) **FIGURINE**

- (71) Applicant: **MEGA Brands Inc.**, Montreal (CA)
(72) Inventors: **Sylvain Charria**, Montreal (CA);
Thierry Beauregard, Boisbriand (CA)
(73) Assignee: **MEGA Brands Inc.**, Montreal, Quebec
(CA)
(**) Term: **15 Years**
(21) Appl. No.: **29/608,816**
(22) Filed: **Jun. 26, 2017**

Related U.S. Application Data

- (63) Continuation-in-part of application No. 29/604,606, filed on May 18, 2017, now Pat. No. Des. 829,127, which is a continuation of application No. 29/560,971, filed on Apr. 12, 2016, now Pat. No. Des. 790,395.

CLAIM

The ornamental design for a figurine, as shown and described.

DESCRIPTION

FIG. 1 is a top isometric perspective view of a first embodiment of a figurine showing the new design; FIG. 2 is a front elevational view thereof; FIG. 3 is a rear elevational view thereof; FIG. 4 is a side elevational view thereof; FIG. 5 is an opposite side elevational view thereof; FIG. 6 is a top plan view thereof; FIG. 7 is a bottom plan view thereof; FIG. 8 is a top isometric perspective view of a second embodiment of a figurine showing the new design; FIG. 9 is a front elevational view thereof; FIG. 10 is a rear elevational view thereof; FIG. 11 is a side elevational view thereof; FIG. 12 is an opposite side elevational view thereof; FIG. 13 is a top plan view thereof; and, FIG. 14 is a bottom plan view thereof.

The broken lines illustrate portions of the figurine that form no part of the claimed design.

1 Claim, 14 Drawing Sheets
